UNITED STATES PATENT OFFICE.

LÉON PAUL CONARD, OF LONDON, ENGLAND, ASSIGNOR OF TWO-THIRDS TO CHARLES FERDINAND VEIT AND GEORGE DICKMAN, BOTH OF SAME PLACE.

BUTTON.

SPECIFICATION forming part of Letters Patent No. 324,303, dated August 11, 1885.

Application filed January 23, 1885. (No model.)

To all whom it may concern:

Be it known that I, LÉON PAUL CONARD, a citizen of the Republic of France, residing at London, England, have invented a new and 5 useful Improvement in Buttons, of which the following is a specification.

My invention consists in the combination, with a button-head and the shank, of a spring-pressed shell which fits over or in the button-10 head, and is capable of rotary motion, leaves hinged to the shank, projections formed on said leaves, a cam adapted to engage the projections on the leaves, and a rod which connects the cam with the shell, and also in the combination, 15 with a button-head and the shank, of a spring-pressed shell which fits over or in the button-head and is capable of rotary motion, a projection on the shell and a depression on the button-head, or vice versa, for locking the 20 shell, leaves hinged to the shank, projections formed on said leaves, a cam adapted to engage the projections on the leaves, and a rod which connects the cam with the shell.

In the accompanying drawings, Figure 1 represents a side elevation of my improved button 25 when in its normal position. Fig. 2 is an end elevation of the same with part broken away. Fig. 3 is an end elevation when the spring-pressed shell is rotated. Fig. 4 is a horizontal section in the plane xx , Fig. 2. Fig. 5 is a 30 bottom view. Fig. 6 is a vertical section in the plane yy , Fig. 7, of the spring-pressed shell and the shank detached. Fig. 7 is a bottom view of the same.

Similar letters indicate corresponding parts. 35 In the drawings, the letter A designates the shank of the button, which has the hollow button-head B rigidly secured to one of its ends, and which shank may be made either hollow, slot-40 ted, or, as shown in the drawings, may have drilled into it a hole, a , which extends in the direction of its length. C is a shell adapted to be fitted over the button-head B, and it is subjected to the action of the spring b , coiled 45 in the button-head. One end of the spring b is secured to a post, c , on the bottom of the button-head, or in any other suitable manner,

and the other end is fastened to a hook or post, c' , on the shell C, Figs. 2 and 6.

To the other end of the shank A, before mentioned, are hinged two leaves, D D', the hinges d and d' of the two leaves being arranged alternately—that is to say, so arranged that one hinge, d , and one, d' , will be respectively the same distance from the center, or facing 55 each other.

On the inner two hinges, d and d' , are formed projections e and e' , which projections are adapted to be engaged by a cam, E, which is connected with the shell C by a rod, f , and has two teeth 60 or projections, g and g' , which, when given a rotating motion, engage the projections e and e' .

Instead of forming the projections e and e' on the respective hinges, the same can be formed directly on lugs formed on the leaves D and D'; but the method first described is considered the most expedient. The action of the coiled spring b tends to keep the shell C in the position shown in Figs. 2, 3, and 4, and when the shell occupies this position the leaves D and D' are 70 extended—that is to say, are in a plane parallel to plane of the button-head.

When the button is to be inserted in the button-hole of a cuff or the like, the shell C is rotated in the direction of the arrow, Fig. 4, 75 whereby the cam E is rotated in the same direction and engages the projections g and g' on the leaves D and D', and the same are brought into the position shown in Fig. 3, and in order to hold them in this position, so as to facilitate the convenience of its insertion, a small recess, h , is formed on the inner surface of the shell C, and a corresponding small projection, h' , is made in the button-head B, both recess and projection being in such a position that when the 85 leaves are folded in the position shown in Fig. 4 the projection engages the recess. When it is desired to extend the leaves, a slight twist of the shell C will disengage the projection from the recess, and the force of the spring b 90 will return the shell C to its original position.

In the drawings, the cam E is shown as extending beyond the plane of the leaves when the same are extended; but in practice I place

the cam so as to fall within or below the plane of the leaves, so that the same can in no manner injure the person wearing the buttons.

What I claim as new, and desire to secure by Letters Patent, is—

1. The combination, substantially as hereinbefore described, with the button-head B and the shank A, of a spring-pressed shell, C, which fits over or in the button-head, and is capable of rotary motion, the leaves D D', hinged to the shank, the projections e e', formed on said leaves, the cam E, adapted to engage the projections on the leaves, and the rod f, which connects the cam with the shell.

15 2. The combination, substantially as hereinbefore described, with the button-head B and the shank A, of a spring-pressed shell, C, which

fits over or in the button-head, and is capable of rotary motion, a projection, h, in the shell, and a depression in the button-head for locking the shell, the leaves D D', hinged to the shank, the projections e e', formed on said leaves, the cam E, adapted to engage the projections on the leaves, and the rod f, which connects the cam with the shell.

In testimony whereof I have hereunto set my hand and seal in the presence of two subscribing witnesses.

LEON PAUL CONARD. [L. S.]
